UNITED STATES PATENT OFFICE.

HENRY DE KERGUÉLIN, OF LITTLE FALLS, NEW JERSEY, ASSIGNOR TO STEPHEN SANFORD & SONS, OF AMSTERDAM, NEW YORK.

DESIGN FOR CARPET.

SPECIFICATION forming part of Design No. 25,653, dated June 16, 1896.

Application filed May 4, 1896. Serial No. 590,229. Term of patent 31 years.

To all whom it may concern:

Be it known that I, HENRY DE KERGUÉLIN, a citizen of the United States, residing at Little Falls, county of Passaic, State of New Jersey, have invented or produced a new and original Design for a Pattern to be Wrought into Carpetings, in such coloring as may be designed; and I do hereby declare that the illustration accompanying this specification gives and conveys to any one skilled in the art of carpet weaving and manufacture a clear understanding of the same and is sufficient to enable such person to use my invention.

What I claim as my invention, and desire to secure by Letters Patent, is—

The design for carpets, substantially as shown in the illustration accompanying this specification.

H. DE KERGUÉLIN.
